UNITED STATES PATENT OFFICE

CHARLES WALES, OF LA GRANGE, ILLINOIS, ASSIGNOR TO WESTERN ELECTRIC COMPANY, INCORPORATED, OF NEW YORK, N. Y., A CORPORATION OF NEW YORK

APPARATUS FOR ASSEMBLING AND TREATING ARTICLES

Application filed December 16, 1926. Serial No. 155,148.

This invention relates to apparatus for assembling and treating articles, and more particularly to an apparatus for assembling incandescent lamps.

5 A type of incandescent lamp, for instance, a telephone switchboard lamp may comprise a sealed glass bulb having a pair of electrical contacts in the form of metallic plates fixed at one end thereof to diametrically opposite points of the bulb and contacting with leading in wires connected to a filament mounted in the bulb, the opposite ends of the contacts being imbedded in a base composed of insulating material. It 10 has been the practice heretofore in some instances to attach the contacts, previously assembled with their associated base, to the bulb by a hand method which has proved costly and which has not resulted in a uniformly assembled product as the accurate assembly depended entirely upon the skill of the operator.

The object of this invention is to provide 15 an apparatus for automatically assembling and treating articles, particularly incandescent lamp parts, expeditiously, accurately and securely with a minimum of cost.

In accordance with the general features 20 of this invention as applied to an apparatus for automatically assembling the previously assembled contacts and bases with a sealed evacuated glass bulb of a telephone switchboard lamp, a plurality of bulbs are advanced due to the intermittent operation of a carrier to a position where predetermined amounts of an adhesive material, such as 25 glue are applied at diametrically opposite points to each of two adjacent bulbs. While in a succeeding position mechanism including 30 a plurality of adjustable fingers become effective for separating the contact springs of a corresponding number of assembled contacts and bases sufficiently to allow them to be assembled on the bulbs over the applied adhesive, this assembly being effected

35 by moving the contacts downwardly over the bulbs. After this operation the contacts are subjected to pressure in such a manner as to press them firmly on the bulbs and to adjust them in predetermined relation thereto. To prevent possible displacement of the contacts the carrier and the assembled bulbs and contacts pass directly 40 from the assembly positions to an oven wherein they remain until the adhesive has 45 completely dried, after which the assembled articles are automatically ejected.

50 Other objects and advantages of this invention will more fully appear from the following detailed description taken in connection with the accompanying drawings 55 illustrating one embodiment thereof, in which

60 Fig. 1 is a general plan view of a telephone switchboard incandescent lamp assembling apparatus embodying the features of this invention, showing the relative positions of the various mechanisms, including an endless carrier and an oven 65 through which the completed assemblies 70 pass to dry the applied adhesive;

Fig. 2 is a fragmentary elevation thereof, partly in section;

Fig. 3 is an enlarged fragmentary plan view of Fig. 1;

Fig. 4 is an elevation thereof, partly in section;

Fig. 5 is an end view looking toward the left of Fig. 4;

Fig. 6 is an enlarged fragmentary vertical section on the line 6—6 of Fig. 3;

Fig. 7 is a plan detail section taken on the line 7—7 of Fig. 6;

Fig. 8 is a fragmentary plan detail section taken on the line 8—8 of Fig. 6;

Fig. 9 is an enlarged vertical fragmentary detail section taken on the line 9—9 of Fig. 6 showing the adhesive applying mechanism;

Fig. 10 is a similar partial view thereof

showing the mechanism upon completion of applying a patch of adhesive upon opposite sides of the bulb;

Fig. 11 is an enlarged vertical fragmentary detail section taken on the line 11—11 of Fig. 6 showing the base assembly transferring mechanism;

Fig. 12 is a similar view showing the mechanism upon completion of transferring the base assemblies to the lamp bulbs;

10 Fig. 13 is an enlarged vertical fragmentary detail section taken on the line 13—13 of Fig. 4 showing the mechanism for pressing the contacts supported by the base against the bulb to spread the adhesive;

15 Fig. 14 is an enlarged plan view of the mechanism for ejecting the completed lamp assemblies from the apparatus upon emerging from the drying oven;

20 Fig. 15 is a vertical section taken on the line 15—15 thereof;

Fig. 16 is an enlarged plan detail section of a wind motor mounted in the oven for facilitating the movement of the endless carrier through the oven;

25 Fig. 17 is an enlarged vertical detail section taken on the line 17—17 of Fig. 2 showing the endless carrier driving mechanism mounted in the oven and associated with the wind motor illustrated in Fig. 16.

30 Fig. 18 is an enlarged fragmentary detail vertical section through a bulb container supported upon the endless carrier, supporting a lamp bulb and showing one of the leading in wires which contact with the plate contacts in the final assembly of the lamp;

Fig. 19 is an enlarged detail view of an adhesive applying finger showing the means for adjusting it laterally on the bulb;

40 Fig. 20 is a side view thereof looking toward the left of Fig. 19;

Fig. 21 is an enlarged vertical section on the line 21—21 of Fig. 4 showing the 45 manner of supporting the base assembly magazine in operative position;

Fig. 22 shows an assembly comprising a pair of plate contacts with their interconnecting base for one type of telephone switchboard lamp;

Fig. 23 shows the final assembly of a telephone switchboard lamp as effected by the apparatus of this invention, and

50 Fig. 24 is a fragmentary detail section taken on the line 24—24 of Fig. 3 showing the cam operating means for the base assembly transferring mechanism.

Referring to the drawings wherein like reference numerals designate like parts throughout the several figures and more particularly to Figs. 1 to 5, inclusive, of the drawings, the assembling apparatus and an associated oven 37 is shown as mounted upon a base or frame 45 equipped with supporting standards, the lower ends of which

are shown fragmentarily to conserve space. Upon the underside of the frame 45 is a motor 46 (Fig. 2) which drives a horizontally disposed revolvable shaft 47 journaled upon a frame 48 mounted upon the upper face of the frame 45 (Figs. 3, 4 and 5), through a belt drive 49. The shaft 47 carries a worm 52 meshing with a worm wheel 53 (Fig. 5) rotatably mounted upon a horizontally disposed shaft 54 journaled on the frame 45. Splined to the right end of the shaft 54 (Fig. 3) is a driven jaw clutch member 55 adapted to be moved into and out of engagement with a driving clutch surface 56 provided on the worm wheel 53 by a pivotal hand lever 59, a bifurcated end thereof being provided with diametrically opposed pins 60 which project into an annular channel 61 formed in the driven clutch member 55. The lever 59 is arranged to be retained in either its inoperative or operative positions by a latch mechanism 62, the lever being shown in the drawings in its operated position, consequently the clutch members 55 and 56 are engaged.

Secured to the rotary shaft 54 within the frame 48 is a plurality of cam wheels 63, 64 and 65 (Figs. 3, 5 and 24), the purpose of which will be referred to shortly hereinafter. The rotary motion of the shaft 54 is transmitted to a horizontally disposed shaft 66 and in turn to a vertically disposed shaft 67 by a plurality of cooperating bevel gears 68—68, the shafts 66 and 67 being journaled upon the frames 45 and 48 (Figs. 3 and 4). Fixed to the shaft 67 is a crank 69 carrying a pin 70 which operates a Geneva movement plate 73 in the usual manner, the plate being fixed to a stub shaft 74, journaled as indicated at 75 upon the upper surface of the frame 45. Secured to the shaft 74 is a sprocket wheel 76, the intermittent motion of which is transmitted to the carrier 30 (Figs. 4, 6 and 7).

Carrier for bulbs and completed lamp assemblies

A carrier 30 which comprises an endless sprocket chain of a usual construction, each link of which is provided upon its upper face in axial alignment with its pivotal points with a pair of cup-shaped containers 80, best shown in Fig. 18, adapted to have positioned therein, in one position of the carrier, by an attendant a lamp bulb 81, also shown in Fig. 23. The bulbs 81 are positioned in the containers 80 in a predetermined position, which will be described in detail in the general description of operation to be given hereinafter, and to maintain the bulbs in such position during their subsequent travel there is provided a vertically disposed leaf spring 82 (Fig. 18) secured at its lower end to the container 80 within one of a pair of vertical slots 83

formed therein and adapted to press against the periphery of the bulb. Also provided on the container are a pair of oppositely disposed slots 79, the purpose of which will be made apparent as this description progresses. The endless carrier 30 or sprocket chain is guided throughout its travel by a plurality of suitably journaled sprocket wheels 84 and in addition at various points 10 between the sprocket wheels the carrier is supported by and slides upon rail members 87. The carrier 30 in its passage through the oven 37 travels a circuitous path and the means for supporting and guiding it there- 15 in and an auxiliary propelling means 88 therefor, illustrated in Fig. 16, will be described in connection with the description of the oven to be given hereinafter.

Mechanism for positioning the bulbs at the bottom of the containers

Referring to Fig. 1, as the intermittently operated carrier 30 with the bulbs 81 moves in the direction indicated by the arrows and 25 just before it comes to the point where adhesive is applied to the bulbs, the bulbs are moved under a gravity actuated means 31 comprising a presser wheel preferably provided with a rubber surfaced periphery and 30 rotatably mounted upon an arm 89 pivoted to the rail member 87. The weight of the wheel is just sufficient to move the bulbs down to the bottom of the containers 80 against the resistance offered by the springs 35 82 (Fig. 18) associated therewith in case they are not so positioned by the attendant during the loading operation.

Adhesive container

40 Carried upon the upper surface of the frame 45 is a circular container 90 for holding a supply of hot liquid glue or other suitable adhesive composition for use in attaching to diametrically opposite points of 45 the bulbs 81 a pair of contacts 91 assembled upon a base member 94 having insulating properties, such as wood (Fig. 22). The liquid adhesive in the container, the level of which is indicated by a dotted line 95 (Figs. 4 and 5) is preferably heated by an electrical heating element (not shown). An agitator comprising a pair of blades 96 positioned adjacent the inner bottom surface of the container 90 and attached to a rotatable 50 shaft 97 axially mounted in the circular container 90 maintains the adhesive in a constant state of motion, the shaft 97 receiving motion from a shaft 98 through a pair of cooperating bevel gears 99-99 (Figs. 3, 4 and 5), the shaft 98 being driven from the shaft 47 by a belt drive 102. Suitable means is connected to the container 90 as indicated by the numerals 100 (Fig. 3) for condensing the steam arising from the hot 55 liquid glue and returning it to the container 60 65

for the purpose of maintaining a uniform consistency of the glue. This means has not been disclosed, since it is not necessary to a complete understanding of the present invention.

Operating rams

Operatively associated with the cams 63, 64 and 65 are levers 103, 104 and 105, respectively, the levers 103 and 105 each comprising a pair of spaced members rigidly fixed together, the levers being pivoted upon a common shaft 106 journaled in opposite side walls of the frame 48. Rollers 107 carried by the short arms of the levers 103, 104 and 105 are arranged to engage and roll upon the peripheral faces of the rotary cams 63, 64 and 65 (Figs. 3, 5 and 24). Referring particularly to Fig. 24 it will be observed that a pair of levers 104 each carrying a roller 107 upon the short arms thereof are operatively associated with the cam wheel 64. The lower lever 104 is connected to the upper lever 104 by a link member 108, the upper lever being pivoted upon an other shaft 106 also journaled in the opposite side walls of the frame 48. It will be apparent that during a complete rotation of the cam wheel 64, from the position illustrated, the interconnected levers will positively be rocked first 95 in a clockwise direction and thence counter-clockwise about their pivots 106, thereby causing the ram 114 to be reciprocated with a uniform upward and downward motion. To prevent the ram 114 from moving except 100 as acted upon by the cam 64 a spring actuated friction shoe 109 (Figs. 4 and 24) is provided. The shoe 109 may comprise any suitable material retained in frictional engagement with the front face of the ram 114 within a slot formed in the frame 48 by a pair of compression springs surrounding a pair of screws threaded into the frame. Reciprocally mounted in vertical guide ways 110 (Figs. 9 to 12, inclusive) provided in the frame 48 and centered with respect to the path taken by the containers 80 which hold the bulbs 81 are a plurality of rams 113, 114 and 115 operatively connected at suitable points intermediate their ends to the levers 103, 104 and 105, respectively, as indicated in Figs. 5 and 24 wherein the levers 104 and 105 are shown in full and dotted lines, respectively, a bifurcated end of each of the levers being operatively connected to a pin 116 fixed to its associated ram. The peripheral contour of each of the cams 63, 64 and 65, the shape of their associated levers and the point of engagement of the bifurcated ends of the latter with their respective rams are such that the rams in their vertical reciprocation cause the operation of a plurality of associated mechanisms, to be described shortly hereinafter, in a predetermined 125 timed relation. The rams in the operation 120

of the apparatus are moved upwardly by the action of their associated cams and levers and are retracted by suitably mounted tension springs 118, with the exception that no spring is necessary in the case of the levers 104, as will be apparent from the description hereinbefore given.

Adhesive conveyor

Attached to the upper end of the ram 114 is an arm 119 (Figs. 3, 4 and 9) which extends forward and to the right as viewed in Fig. 3 to a point in front of the ram 115. The free end of the arm 119 engages within a notch 120 provided in a vertically reciprocable link arm 121 disposed in front of the ram 114 and carrying at its lower end an adhesive conveyor 122 normally immersed below the level 95 of the adhesive stored in the container 90. The arm 121 is guided at its lower end by the walls of an aperture formed in a cover 123 provided for the container, while other guides 124 (Figs. 5 and 9) carried upon the frame 48 serve to guide it at other points thereof in its reciprocation. The conveyor 122 in its reciprocation is operatively associated with an adhesive applying mechanism 32 which will now be described.

Adhesive applying mechanism

Referring particularly to Figs. 9 and 10 the ram 115 intermediate its ends carries a cross bar 127 which extends through a slot provided in the ram and an equal distance from opposite sides thereof. Pivottally attached to the ends of the arm 127 and upon opposite sides thereof is a pair of depending levers 128. Mounted upon the levers 128 are rollers 129 which engage opposite faces 130 provided upon a pair of stationary plates 131, the faces 130 being provided with cam portions 132 at their upper ends. The rollers 129 are held in engagement with the faces 130 by a tension spring 134, opposite ends of which are secured to each pair of oppositely disposed levers 128. Attached to the lower ends of each of the levers 128 is a depending adhesive applying finger 135, which as clearly indicated in Fig. 9 is normally spaced from opposite sides of the bulb 81, the inner surface of the finger being concave as indicated by the numeral 136 (Figs. 19 and 20) to fit the peripheral face of the bulb 81. Each of the fingers 135 is integral with and depends from a ring-shaped portion 137 of an angular shaped member 138, the top edge of the finger terminating in line with the lower inner edge of the opening in the ring portion 137 for a purpose which will be referred to shortly hereinafter. The angular shaped member 138 is adjustable toward and from the bulb 81 by means of a screw threaded rod 141 journaled in a pair of upwardly extending lugs 142 formed upon the member 138, the rod having a

threaded engagement with the right hand lug 142 (Fig. 19). The rod 141 at one end is rotatably attached to a depending arm of a member 143 which is rigidly fixed to the lever 128, the opposite end of the member 143 being provided with a horizontal shelf portion 144, a nut 145 fixed to the rod 141 bearing thereon and forming a lock for retaining the associated finger 135 in a predetermined normal spaced relation from the bulb 81 after rotating the rod 141 by means of a crank portion 146. In the operation of the apparatus while the adhesive conveyor 122 is moving upwardly the fingers 135 are moving downwardly, the fingers dipping into the conveyor at a point within the container 90 just below the cover 123 thereof, as shown in Fig. 10, thereafter the fingers 135 are raised to the dotted line position, Fig. 9, the conveyor 122 returning to the position thereof also shown in Fig. 9. Upon the fingers 135 reaching substantially the limit of their upward movement they are abruptly moved inwardly toward the periphery of the pair of bulbs 81, (dotted lines Fig. 9) without any appreciable pressure upon the bulbs, thereby applying adhesive thereto, the latter movement caused by the rollers 129 dropping into the cam portions 132 formed upon the plates 131, which movement is assisted by the spring 134. Due to the fingers 135 terminating at their upper ends with the inner circumferential faces of the ring portions 137 it will be apparent that a predetermined quantity of the adhesive will be applied to a predetermined height upon the bulbs 81.

Magazine for supporting base assemblies

A plurality of lamp base assemblies each comprising the pair of contacts 91 and the base member 94 are mounted upon magazines 149 previously loaded and positioned upon opposite sides of the frame 48 whereby the assemblies may be fed into a transferring position two at a time from opposite directions by a mechanism 33. The magazines 149 each comprise a plate turned over along its upper edge to provide two parallel spaced vertical walls 150 and 151 (Figs. 4 and 21), the base assemblies being freely slidable thereon with the contacts straddling the upper edge of the magazine. The wall 150 is provided with a depending handle 152 intermediate its length, while the wall 151 is provided with a lip 153 similarly disposed, which facilitates the mounting of the magazines 149 upon vertical plates 156, one upon each side of the frame 48, fixed to bars 157 mounted upon the frame 45, the plate 156 being entered between the walls 150 and 151 of the magazine with the lips 153 projecting through an aperture 158 provided in a right angle extension of the plate 156. It will be apparent that the lip 153

153 will serve to guide the plate 156 into the space between the walls 150 and 151 of the magazine 149 and upon being mounted in correct position thereon will prevent its 5 longitudinal displacement during the removal of the base assemblies therefrom in the operation of the apparatus. In alignment with the upper horizontal edge of each of the magazines 149 at their inner ends and 10 abutting the inner vertical faces of the plates 156 at one end with their inner or opposite ends having a sliding clearance with the opposite vertical sides of an enlargement 159 provided upon the lower end 15 of the ram 114 are stationary rails 160 (Figs. 6 and 8). At their outer ends the rails 160 are similar in vertical cross-section to the vertical plates 156 but gradually become greater in thickness toward their inner ends 20 adjacent the enlargement 159 of the ram 114, thus causing the contacts 91 to gradually be spread further apart at their lower ends, as the base assemblies are successively fed therewith into operative position with 25 respect to the ram 114, for a purpose which will be apparent as this description progresses. Formed in the lower end face of the enlargement 159 at either side thereof are notches or depressions 161 (Figs. 6 and 30 8), the upper end walls of which are V-shaped to substantially conform to the contour of the upper ends of the base members 94 as indicated at 164 (Fig. 5). Upon the ram 114 reaching the uppermost point of its 35 travel wherein the upper end walls of the depressions 161 are sufficiently above the upper V-shaped ends 164 of the base members 94, the base assemblies are moved from opposite directions upon the rails 160, the inner end base assemblies upon each side 40 of the ram being moved into the depressions 161 by the following mechanism:

Carried upon the frame 45 and arranged in pairs at opposite sides of the frame 48 45 are four wind driven pistons 165 (Fig. 2) disposed to operate in a longitudinal direction and carrying at their inner ends spring controlled fingers 166 arranged to engage the outer base member 94 of the train of 50 base assemblies carried upon the magazines 149. The pistons 165 comprising each pair are arranged vertically, one directly above the other with the fingers 166 carried at their inner ends mounted on carriages 167 (Fig. 3) adapted to slide upon rails 168. For controlling the finger 166 associated 55 with each piston 165, the finger being reciprocally mounted in the carriage 167, there is provided a bell crank lever 171 fulcrumed 60 upon the carriage with one arm thereof pivoted to the finger 166 and its opposite end associated with a leaf spring 172 which normally acts to rock the lever counter-clockwise to maintain the finger 166 in operative 65 position with the base member 94,

as clearly indicated in Fig. 3. When it is desired to retract the finger 166, which is necessary at intervals in the operation of continuously assembling the lamps, as will be described hereinafter, the operator grasps a handle 173 provided upon the carriage 167 and rocks the lever 171 against it and upon release thereof the finger moves back to its normal position. Only one of the fingers 166 of each pair thereof disposed upon opposite sides of the ram 114 is normally in engagement with the outer base member 94 of the associated train of base assemblies, but they are so arranged upon their respective carriage 167 and rail 168 that either one 70 may be so positioned without interference from the other. Each of the pistons 165 is actuated by compressed air supplied from a suitable supply source and directed into the outer end of a cylinder 174 (Figs. 1 and 2) and against the corresponding end of the piston 165 carried therein, the opposite end as hereinbefore described carrying the finger 166. The air admitted to each pair 75 of cylinders upon either side of the ram 114 is controlled by a four-way valve 175 which is manually operated by a handle 176 (Figs. 1 and 2) supported upon the front of the frame 45, within easy access of the attendant. The four-way valve in a well known manner upon operation thereof and suitable associated piping transfers the air pressure from one cylinder to the other. In the operation of the apparatus one of the fingers 166 of each pair thereof intermittently 80 pushes the train of base assemblies carried upon the associated magazines 149 therewith and onto the abutting rails 160 and into operative position within the depressions 161 of the ram 114 ready to be moved 85 downwardly by the ram. Upon the fingers reaching a point indicated by the numeral 179 (Fig. 4) wherein all the base assemblies 90 have been moved from the magazine onto the rail 160, sufficient space is left for the removal of the empty magazine without disturbing the continuous feeding operation and the mounting of a filled magazine in its place in the manner hereinbefore described. The attendant thereupon grasps the handle 173 associated with the idle finger 166 carried by the free piston 165 and engages the finger with the outer base member 94 of the train 95 carried upon the magazine just mounted, the inner base member abutting the operative finger 166. Thereafter upon completion of a feeding movement of the operative finger 166 or during the interval 100 in which the base assemblies are not moving along the rail 160 the attendant with one hand retracts the finger 166 from between the adjacent base assemblies and simultaneously therewith operates the handle 176 105 of the associated four-way valve 175 which transfers the air pressure from the operative 110

piston 165 to the idle piston 165 which thereupon continues the feeding operation, the previously operative piston now idle being freely movable back to a position where the finger 166 carried thereby is adjacent the inner end of the cylinder 174 (Fig. 2). Thus in the operation of the apparatus the fingers 166 comprising each pair thereof upon opposite sides of the ram 114 are alternately used to provide a continuous feed of the base assemblies toward the depressions 161 of the ram 114, a pair thereof passing thereinto during each reciprocation of the ram for transfer to the pair of bulbs previously treated with adhesive and positioned immediately therebelow, as hereinbefore described, by a mechanism 34.

Mechanism for spreading the contacts of the base assemblies and transferring them to the prepared bulbs

Pivots attached at their upper ends to opposite ends of a cross bar 180 fixed within a slot provided in the ram 114 intermediate its ends and extending an equal distance from opposite sides thereof (Figs. 11 and 12) are depending cam levers 181. The lower end of each of the levers 181 is bifurcated and fulcrumed to a centrally disposed bar of a rocking frame 182 (Fig. 12) intermediate its length and providing lever arms unequal in length. Pivots attached at its lower end to the outer or long arm of the frame 182 is a rod 183 having its upper end freely passing through an aperture provided at the top of the frame 48, a nut 186 screw threaded onto the end thereof above the surface through which it extends limits the downward movement thereof. Although the mounting of the upper end of only one of the rods 183 is shown (Fig. 4), the other rod is mounted in substantially the same manner. Surrounding the rod 183 intermediate its length is a coiled compression spring 187, the spring at one end resting against an adjustable collar 188 carried by the rod and its opposite end against the lower end of a sleeve 189 free upon the rod, the spring normally tending to move the rod downwardly. Formed in each of the levers 181 is an elongated slot 190 provided at its lower end with an offset cam portion 193. Stationary pins 194 fixed to the frame 48 extend through the slots which in the reciprocation of the ram 114, to be described hereinafter, causes each of the levers to be rocked alternately in opposite directions about their pivots. Carried upon each of the frames 182 is a pair of wire fingers 195 (Fig. 7) which extend in a direction at right angles to the movement of the carrier, each being centered with a base assembly, as previously described, mounted in the depressions 161 of the ram 114. The inner ends of the fingers are provided with a substantially

right angle extension 196 extending upwardly, which in the operation of the apparatus is hooped under the extreme lower ends of the contacts 91 as shown in dotted outline in Fig. 11. The outer ends of the fingers 195 are associated with an adjustable screw 197 in such a manner that the hooked ends of the fingers may be laterally adjusted with respect to the longitudinal center line of the carrier 30 by merely rotating the screw, the fingers adjacent their inner ends being reciprocally mounted and guided in apertures provided in the frame 182. As clearly shown in Fig. 22 the contact plates 91 of the base assemblies, when not mounted upon the magazine 149 or rail 160, due to the normal spring pressure therein move into engagement with each other at their lower ends. The purpose of the greater thickness of the rails 160 toward their inner ends will now be described. As the base assemblies are fed along the rails toward the depressions 161 of the ram 114, the contact plates 91 will be spread apart from the position shown in Fig. 22, due to the shape of the rails, and further than that shown in Fig. 21 until they are substantially parallel for the purpose of providing sufficient space therebetween for the insertion of a pair of oppositely moving plungers, to be presently described, which retain the plates in a parallel relation until they are engaged at their lower ends by the hooked ends 196 of the fingers 195 which are moved simultaneously upwardly and inwardly to hook thereunder during the downward movement of the ram 114, as will be shortly described.

At the same instant that the base assemblies are entered in the depressions 161 and simultaneously with the movement of the ram 114 downwardly, a pair of horizontally reciprocable plungers 198 (Figs. 6, 8 and 11) are moved from opposite directions into the space thus formed between the contact plates and thereby maintaining the contacts in a substantially parallel position as clearly shown in Fig. 11. The means for operating the plungers 198 in timed relation to the downward movement of the ram 114 and the insertion of the base assemblies in the depressions 161 comprises the following: Referring particularly to Fig. 8, upon the lower end of the rotating shaft 67 is fixed a cam wheel 200 adapted to rock a bell crank lever 201 about its pivot 202 which is disposed equi-distant the ends of a short arm of the lever, a long arm thereof engaging the periphery of the cam wheel 200. A tension spring 203 attached at opposite ends to the long arm of the lever 201 and to a stationary bracket forming a support for the lever maintains the latter in engagement with the cam wheel 200. Pivots secured at one end thereof to opposite ends of the short arm of the lever 201 are link rods 204, the opposite

ends thereof being similarly secured to the outer ends of a pair of slide plates 206, the inner ends of the latter carrying the plungers 198. The upper face of the plates 206 slide along the bottom of the rails 160, while the opposite face thereof rests upon a stationary guiding and supporting plate 207 (Fig. 6). The inner opposite ends of the rails 160 are provided with slideways 209 for guiding the plungers 198 in their reciprocation (Fig. 6), the plungers being connected to the slide plates 206 by intermediate connecting members 210 secured to the upper surfaces of the plates. Thus in the operation of the apparatus the cam wheel 200 will be rotated and through the associated lever 201 and the other cooperating members the plungers 198 in timed relation to the other elements of the apparatus will be moved into the V-shaped spaces 199 formed between the contact plates 91 of the lamp assemblies and thereafter withdrawn.

In the movement of the ram 114 upwardly the fingers 195 are moved from the position shown in Fig. 12 to the full line position thereof shown in Fig. 11. Just before reaching the latter position a pair of vertically reciprocable plungers 211 carried in slideways provided in opposite ends of the enlargement 159 of the ram 114 are caused to move downwardly, in timed relation with the upward movement of the fingers 195, a predetermined distance by the following mechanism: Fixed to the shaft 66 (Figs. 3 and 4) is a cam wheel 212 and engaging the cam face thereof is a roller 214 carried upon one end of a lever 215 secured to a shaft 216 journaled upon the frame 48. Upon the forward end of the shaft 216 is secured a pair of levers 217, the free ends thereof directed toward the ram 114 and upon the front and rear side thereof, as shown in Fig. 3. Depending from the free ends of the levers 217 are rods 218 supporting upon their lower ends the previously mentioned plungers 211. A tension spring 221 having opposite ends thereof secured to the forward lever 217 and the frame 48 serves to maintain the roller 214 in contact with the cam wheel 212. During the downward movement of the plungers 211 they engage the upper surface of the upwardly moving frames 182 adjacent their inner ends and at a predetermined distance below the lower ends of the contact plates 91 of the base assemblies and thereafter move upwardly along with and in contact with the frames 182 until the hooked ends 196 of the fingers 195 are about to engage the lower ends of the plates when they are suddenly moved upwardly and away from the frames 182, thereupon the compression of the springs 187 serves to rock the outer ends of the frames 182 downwardly, thereby moving the inner ends thereof quickly upwardly,

the frames pivoting upon the levers 181. This upward movement of the inner ends of the frames 182 occurs at substantially the same instant that the offset portion 193 of the slot 190 provided in each of the levers 181 engages the stationary pin 194 which it will be apparent causes the levers to be rocked toward each other about their pivots upon the cross bar 180 and consequently carrying the fingers 195 toward each other simultaneously with the upward movement of the inner ends thereof and thereby hooking the right angle extensions 196 thereof under the lower ends of the contact plates 91, as shown in dotted lines in Fig. 11. Immediately upon the completion of the latter movement of the fingers 195 the ram 114 starts to move downwardly, the offset portions 193 of the slots 190 formed in the levers 181 instantaneously moving away from the pins 194 and causing the levers 181 to be rocked outwardly, thereby flexing the contact plates 91 to the position shown in dotted lines in Fig. 11, the continued movement downwardly of the ram slipping the contact plates 91 down over the previously treated and positioned bulbs as clearly shown in Fig. 12, the ram 114 being at its lowermost position. As clearly shown in the dotted line position of the contact plates 91 and the fingers 195, the plates during their downward movement are spread such a distance that they will not engage the bulb 81 or the adhesive patches applied thereto until the fingers release their hold thereon. Upon the ram 114 reaching its lowermost position the lower ends of the plates abut the upper surface of the containers 80, the ends of the fingers 195 moving into the slots 79 formed in the containers 80 hereinbefore described and also into slots 224 formed in vertical members 225 forming a housing upon opposite sides of the carrier 30, the depth of the slots 79 and 224 and the movement of the fingers being such that the latter are withdrawn from engagement with the plates 91 and assume the position shown in Fig. 12. Fixed to one of two pair of depending levers 226, the purpose of which will shortly be made apparent, is a yoke member 227 provided with depending arms 228 upon each side thereof, the lower ends of the arms having right angle portions 229 which, as clearly shown in Figs. 11 and 12, extend toward the carrier 30 and lie very close to the base assemblies positioned in the depressions 161 formed in opposite sides of the enlargement 159 of the ram 114. The portions 229 of the yoke member 227 serve as guards during the transfer of the base assemblies from the position thereof shown in Fig. 11 to that shown in Fig. 12 to prevent the base assemblies from falling sideways as viewed in Fig. 6 during their transfer.

Mechanism for pressing the contacts against the bulb

Pivots supported upon each of the stationary pins 194 is the pair of depending levers 226 (Figs. 4 and 13) of a mechanism 35 provided to press the contacts 91 against the bulb and which are aligned as viewed in Fig. 4 with the vertical center of the pair of bulb containers 80 to the left of the containers holding the bulbs which just previously had the base assemblies mounted thereon. The lower ends of each of the levers 226 is formed with a right angle extension or finger 231, the end face of which is equipped with an insert 232 composed of flexible material for engaging the contact plates 91, which operation will shortly be described. The upper ends of each of the levers 226 is provided with a comparatively short inwardly extending arm 233, the arms upon one pair of levers overlapping the ends of the arms upon the oppositely disposed pair of levers. The four arms 233 at their point of overlap, which is in line with the vertical axis of the ram 113, are spaced in close formation laterally whereby the lower end surface of an enlargement formed on the ram may simultaneously engage all arms. Coiled tension springs 234 having their ends secured to the oppositely disposed levers 226 of each pair serve to normally rock the levers inwardly to carry the flexible inserts 232 into engagement with the contact plates 91 with sufficient pressure to spread the adhesive and press them firmly against bulbs. The ram 113 in timed relation with respect to the movement of the rams 114 and 115 moves downwardly to engage the arms 233 and thereby rocks the levers 226 outwardly against the action of the springs 234 and retracts the inserts 232 from the contact plates 91, a movement upwardly of the ram it will be evident permits the springs to draw the inserts toward each other and into operative engagement with another set of contact plates moved into position by the carrier 30. The period during which the inserts 232 are in engagement with the contact plates 91 occurs during the period in which the contact spreading fingers 195 and the ram 114 are functioning to transfer base assemblies from the level of the tracks 160 to the bulbs 81, as hereinbefore described, and consequently the guards 229 occupy the position shown in Fig. 11, they being carried by one of the levers 226.

Mechanism for pressing the base assembly longitudinally upon the bulb

Upon a bracket 237 fixed to the frame 48 adjacent its upper surface and upon its left hand side is pivotally mounted a lever 238 for actuating a mechanism 36 for pressing

the base assembly longitudinally upon the bulb, the lever being bifurcated at its right end (Fig. 4). A pin 239 extending forward from the upper end of the ram 113 operatively engages within the bifurcated end of the lever 238, the opposite end of the lever being provided with an aperture through which freely extends a rod 240. A pin 241 passing through the rod 240 above the upper face of the lever 238 provides means whereby the rod will be lifted upwardly upon a clockwise movement of the lever, caused, it will be apparent, by a downward movement of the ram 113. An arm 244 integral with the bracket 238 provides a journal or guide for the vertically reciprocal rod 240. Referring to Fig. 6, upon the lower end of the rod 240 is mounted a shoe 245 of such a length that it spans two lamp assemblies. In the operation of the apparatus and in timed relation to the movement of the carrier the lever 238 is rocked away from the pin 241 carried by the rod 240 which permits the shoe to move downwardly by the force of gravity into engagement with the upper surface of the base members of the lamp assemblies positioned thereunder, added pressure being given to the shoes by a collar 246 of suitable weight fixed to the rod 240. As hereinbefore described the presser wheel 31 insures that the bulbs 81 will be positioned at the bottom of the containers 80 and with the pressure of the shoe 245 the lower end surfaces of the contact plates 91 will be moved into engagement with the top surface of the containers 80, thus insuring that the over-all length of the lamps will be uniform, it being understood that the applied adhesive at this stage in the assembly of the lamp parts is still in a plastic state.

Drying oven

An oven 37, Figs. 1 and 2, for drying the adhesive comprises a rectangular shaped housing positioned at the left of the frame 45 upon standards 250, shown fragmentarily. Within the housing is preferably mounted an electrical heating element connected to a suitable source of current (both not shown) for furnishing sufficient heat therein to thoroughly dry the adhesive and thereby attach the lamp base assemblies 94 securely to the bulbs 81 during their circuitous travel therethrough, which will be presently described. As shown in dotted outline (Fig. 1) at each corner of the housing upon a frame 251 (Fig. 2) is journaled a pair of vertical shafts 252 and 253, all of the shafts being freely rotatable upon the frame except the pair at the lower left corner of the housing (Fig. 1), which are driven in a manner to be presently described. Each of the shafts 252 and 253 supports a plurality of the sprocket wheels 254 around which the carrier or sprocket chain 30 is wrapped, the

sprocket wheels being so arranged that as the chain is propelled one link at a time intermittently, it ascends from the outer set of shafts 252 from the bottom to the top of the oven, each convolution of the chain ascending a sufficient distance to leave space for the lamps mounted on the convolution of the chain immediately therebelow. The chain upon reaching the top of the oven travels to the sprocket wheels 253 mounted upon the inner set of shafts and descends by the same method to the level at which it entered the oven and at one side thereof (Fig. 1).

It would be impracticable on account of the friction created by the chain and its resistance to lateral movement to cause it to move along its entire length alone through the action of the main driving sprocket wheel 76 as hereinbefore described. It is, therefore, necessary to drive each convolution of the chain independently and this is accomplished by the propelling means 88 hereinbefore referred to and which will now be described. Positioned within the housing of the oven 37 adjacent the upper end of the frame 251 (Figs. 1, 2 and 16) is a wind motor 88 comprising two opposed air pistons 256 carried in cylinders 257 and 258, the pistons being integral with a common piston rod 259. Formed upon the rod 259 is a rack 260 in mesh with a gear wheel 261 which upon receiving motion from the right piston 257 (Fig. 16) transmits a counter-clockwise rotary movement to a shaft 263 journaled upon the frame 251 through a usual pawl and ratchet mechanism 264 operatively associated with the wheel 261 and shaft, respectively. Upon a movement of the left piston 258 toward the right it will be apparent that the gear wheel 261 will idly rotate on the shaft 263 in a clockwise direction, the pawl attached to the gear idly riding over the ratchet teeth. Thus the shaft 263 is rotated a predetermined amount for each reciprocation of the wind motor 88, which movement is transmitted to the inner shaft 253 positioned at the lower left corner of the oven 37, as viewed in Fig. 1, by a sprocket wheel 265 attached to the upper end of each of the shafts 263 and 253 and an interconnecting chain 266. Air is admitted to the cylinders 257 and 258 at predetermined uniform intervals by an ordinary four-way valve 267 (Fig. 3), the inlet port of which is connected by a pipe 268 to a supply of compressed air (not shown). Oppositely disposed outlet ports of the valve 267 are connected by separate pipes 269 to the cylinders 257 and 258 as indicated in Figs. 2 and 16. A fourth port of the valve is connected by a pipe 270 to a point 273 (Fig. 1) positioned at the left of the ejecting mechanism 39 and arranged immediately above the empty containers 80 of the carrier 30 for di-

recting an intermittent blast of air into the containers to remove any particles of dried adhesive or other matter which may be positioned therein. An upwardly extending stem 274 of the valve 267 carries a sprocket wheel 275 which is operatively connected to a sprocket wheel 276 fixed to the constantly driven shaft 67 by an interconnecting chain 277.

The admission of air to the right cylinder 257, which as hereinbefore described, transmits motion to the outer shaft 253 positioned at the lower left corner of the oven 37, as viewed in Fig. 1, is timed in such a manner that it occurs slightly subsequent to the intermittent movement of the sprocket wheel 76. As a result of this previous actuation of the sprocket wheel 76 slackness is formed in the carrier chain 30 between the idler wheel 84 and the sprocket wheel 254 (Figs. 1 and 2) which the chain first engages within the oven 37 as indicated in dotted lines at 278 (Fig. 3). This slackness in the chain 30 occurs before the thrust of the piston 256 of the cylinder 257 occurs, thereby preventing any deleterious strain being imparted to the chain due to the unrestrained movement of the piston upon air being admitted to the cylinder which would tend to move the chain 30 at a greater speed than the movement of the sprocket wheel 76 permits. To support and guide the chain 30 at this point there is provided a pivotal arm 281 supporting a sprocket wheel 282, the arm being freely mounted upon the stud carrying the adjacent idler sprocket wheel 84 (Fig. 3), the chain being guided between the sprocket wheels 282 and 84. The full line position of the arm 281 and the sprocket wheel 282 indicates the normal position thereof during the interval in which the carrier 30 is not traveling. Upon the sprocket wheel 76 being indexed by the Geneva movement plate 73 the arm 281 is rocked counter-clockwise to the dotted line position thereof (Fig. 3), which movement is assisted by a coiled spring 283 under tension at this time and having one end fixed to the arm 281 and its opposite end to a stationary pin (not shown) fixed to the frame 45. Immediately thereafter air is admitted to the cylinder 257 and through the thrust of the piston 256 the slack in the chain at the point is taken up and the carrier chain 30 as a whole being advanced one step, the arm 281 being rocked clockwise to the full line position thereof with the spring tending to check the sudden thrust of the piston.

Mechanism for trimming lamp base

Immediately upon being discharged from the oven 37 the lamp assemblies are moved under a polishing wheel 38 (Figs. 1 and 2) fixed to a shaft 285 which is connected to a source of power (not shown). The

wheel 38 is revolved at a very high rate of speed and positioned vertically above the upper end of the base members 94 in such a manner that the periphery of the wheel will barely engage the tapered end of the base members passing thereunder and cause them to be polished to remove any roughness thereof and also trimming them sufficiently to assure that the over-all length of the completed lamps will be uniform.

Ejecting mechanism

Upon passing under the wheel 38 the carrier 30 intermittently travels around a pair of sprocket wheels 84 (Fig. 1) positioned comparatively close to the oven. Associated with the upper wheel 84 as viewed in Fig. 1 is a mechanism 39 for ejecting from the containers 80 of one link of the chain 77 a pair of completed lamp assemblies during each interval in which the carrier 30 is stationary. The mechanism 39, referring particularly to Figs. 14 and 15, comprises a pair of vertically disposed plates 286 supported upon the frame 48 and in the operation of the carrier 30 a pair of lamps is halted equidistant the plates and above an upper surface at the left end thereof as viewed in Fig. 15. Journaled upon the plates 286 at the right end thereof is a shaft 287 which is operatively connected to a shaft 288 similarly journaled below the shaft 287 but near the left end of the plates by cooperating sprocket wheels 289 and an interconnecting chain 290 (Fig. 14). The shaft 287 is driven from the shaft 66 journaled upon the frame 48 by a pair of cooperating sprocket wheels 293 (Figs. 1, 3 and 4) fixed to the shaft 66 and a shaft 294 (Figs. 1 and 14) by an interconnecting chain 295, the shaft 294 being operatively connected to the shaft 287 by a pair of cooperating bevel gears 296. Reciprocally and pivotally carried between the plates 286 is a plate 297, one end of which is directed toward the carrier 30 with its upper surface normally on a plane slightly below the lower end of the base members 94 of the completed lamps as positioned in the containers 80 of the carrier 30. The opposite end of the plate 297 carries a roller 300 mounted within a slot formed intermediate the sides thereof and upon a pin 301 extending therethrough, the pin also extending through an enlargement 302 of the plate and through horizontal slots 303 formed in the plates 286 and centered with respect to the axis of the shaft 287, the ends of the pin 301 supported in the slots providing a variable fulcrum for the plate 297. The left end of the plate 297 as viewed in Figs. 14 and 15 is provided with a pair of notches 304 having a spacing identical with the lamps supported in the pair of containers 80 intermittently stepped into position between the plate 286, as here-

inbefore described. Pivotally carried upon the upper surface of the plate 297 as indicated at 305 is a pair of fingers 308, the fingers upon opposite sides resting normally against pins 309 fixed in the plate 297, they being tied together by a coiled tension spring 310. The inner sides of the fingers 308 are normally in overlapping relation with the outer sides of the notches 304 provided in the plate 297, as shown in dotted lines in Fig. 14. To the underside of the plate 297 adjacent the end thereof provided with the notches 304 is a pair of depending levers 311, one of which is illustrated in Fig. 15. Between the levers at their lower ends is a roller 312 carried upon a pin 313, opposite ends of which extend through vertically disposed slots 314 provided in the plates 286, the slots being centered directly above the axis of the shaft 288. Fixed to the shafts 287 and 288 are cam members 317 and 318, respectively, arranged to engage the rollers 300 and 312, respectively, in a predetermined sequence to first move the plate 297 toward the left and thus associating the notches 304 under the lower ends of the base members 94 and adjacent the edges of the contact plates 91 of the pair of lamps previously moved into position, the fingers 308 turning on their pivots 305 but closely hugging the contact plates under the action of the spring 310. Upon the notched plate 297 being thus positioned the cam 318 has been revolved to a point where it operates to move the plate in a clockwise direction about its fulcrum point through the associated roller 312 and levers 311, thus lifting the completed lamps from within the containers 80. Connected at one end to a lug adjacent the pivotal point of the lever 311 with the plate is a coiled tension spring 319, the opposite end thereof being fixed to a stationary point 320, the spring it will be apparent serves to retract the plate 297 to its normal position as shown in Figs. 14 and 15 as the high point of the cam 317 recedes from the roller 300. Hinged to a bolt 321, which is one of a plurality of bolts for holding the plates 286 in spaced relation, is a plate 322 with its free end normally in line with the left end of the plate 297 (Figs. 14 and 15) and arranged to engage the upper surface thereof at all times. As the plate 297 moves to the left, as hereinbefore described, it uncovers the notches 304 for reception of the lamps and as the plate moves back to its normal position with the lamps, the latter are pushed therefrom by the left end of the plate 322 as the lamps are moved into engagement therewith. The ejected lamps drop into a space 323 formed between the path of the carrier 30 and the end of the plate 297 and upon an inclined chute 324 preferably made of felt to eliminate breakage of the lamps, and thence into a recepta-

cle 325. The empty containers 80 of the carrier continue toward the right as viewed in Fig. 1 for reloading by an attendant.

The operation of this apparatus is as follows:

Referring to Fig. 1 an attendant assumes a position adjacent the ejecting mechanism 39, as indicated by the broken line circle 327, and as the carrier 30 intermittently moves toward the right, as indicated by the arrow, a pair of bulbs 81 are positioned in the containers 80 of the carrier. Another attendant positioned as indicated by a broken line circle 328 rotates the bulbs 81 within the containers 80 so as to arrange a pair of leading in wires 329 (one of which is shown in Fig. 18) extending upwardly from opposite sides of the bulb so that they will be directed toward opposite sides of the carrier 30. The wires 329 in the completed assembly of the lamp form an electrical path for current supplied to the plates 91 to light the filament carried in the bulb, the plates engaging the bulb from opposite sides of the carrier as hereinbefore described in detail. As the carrier 30 travels intermittently in the direction indicated by the arrows (Fig. 1), the bulbs 81 move first under the gravity actuated pressing wheel 31, which serves to move them down to the bottom of the containers 80 in case they are not so positioned by the attendant. Thence successively a pair of bulbs are stopped between the adhesive applying fingers 135 which are operated as hereinbefore described to print restricted areas of hot plastic adhesive upon opposite sides of the bulbs. While the adhesive is being applied to one pair of bulbs, a pair of base assemblies is being transferred from the magazines 149 to the mechanism 33 for supporting and feeding the assemblies and slipped down over a pair of bulbs just previously treated with adhesive by the mechanism 34, all in a manner hereinbefore described in detail. During the mounting of the base assemblies upon a pair of bulbs as just mentioned, the just previously assembled bulbs and base assemblies are positioned in operative relation with the mechanism 35 which acts to press the contact plates 91 toward each other to spread the adhesive and provide a predetermined uniform lamp diameter. After leaving the mechanism 35 the assembled bulbs and base assemblies are intermittently moved under the mechanism 36 for pressing the base assemblies longitudinally upon the bulbs to insure that they are still positioned with the end surfaces of the plates 91 abutting the top surface of the containers as positioned by the ram 114 with the assembled lamp parts having a predetermined uniform overall length before their entry in the drying oven 37 which they then pass through, thus uniting the base assemblies with the bulbs. Upon exit from the oven 37 the next and final step is their movement under the polishing wheel 38 which polishes the end of the upwardly projecting base members 94 to remove any roughness thereof and also trimming them sufficiently to again assure that the overall length of the completed lamps will be uniform. The carrier then intermittently travels past the ejecting mechanism 39, where during each interval in which the carrier 30 is stationary, a pair of completely assembled lamps are lifted from the containers 80 in the manner described in detail hereinbefore and deposited in the receptacle 325. As the carrier 30 continues to the right toward the attendant positions 327 and 328 (Fig. 1) a blast of air is intermittently emitted from the pipe 270 at the point 273 and into the empty containers 80 for the purpose of removing any particles of dried adhesive or other matter which may be positioned thereon.

The advantages of the hereinbefore described apparatus are that it is substantially continuous in operation, the only manual operation being that of inserting the lamp bulbs in the containers carried by the endless chain and rotating them to a predetermined position therein as they travel past the attendant positions 327 and 328, respectively; it does not require experienced operators as is necessary in a manual assembly of the lamps, and that the output of the apparatus may be many times greater than that of a single experienced hand operator.

What is claimed is:

1. In an apparatus for assembling an incandescent lamp bulb with its supporting base, means for supporting the bulbs and bases, a receptacle containing an adhesive material, means for transferring adhesive therefrom and applying it to diametrically opposed restricted areas of a bulb, and means for causing a relative movement between the bulb and a base to assemble them in attached relation by the coherence of the adhesive.

2. In an apparatus for assembling incandescent lamp bulbs with their supporting bases, means for supporting supplies of bulbs and bases, a receptacle containing an adhesive material, means for transferring adhesive therefrom and applying it to the outer surface of a bulb, means for causing a relative movement between the bulb and a base to assemble them in predetermined attached relation by the coherence of the adhesive, and means for thereafter polishing and trimming a face of the base.

3. In an apparatus for assembling incandescent lamp bulbs with their supporting bases, means for supporting supplies of bulbs and bases, a receptacle containing an adhesive material, means for transferring adhesive therefrom and applying it to diametrically opposed restricted areas of a

bulb, means for causing a relative movement between the bulb and a base to bring them into assembling relation, and means for applying pressure between the bulb and base to press them into more intimate contact with each other.

4. In an apparatus for assembling incandescent lamp bulbs with their supporting bases, the latter including oppositely disposed separated contact members, means for supporting supplies of bulbs and bases, a receptacle containing an adhesive material, means for transferring adhesive therefrom and applying it to restricted outer areas of a bulb, means for causing a relative movement between the bulb and a base to bring them into assembling relation, means for applying pressure between the bulb and base to press the contact members firmly on the bulb and means for thereafter adjusting them in predetermined attached relation by the coherence of the adhesive.

5. In an apparatus for assembling incandescent lamp bulbs with their supporting bases, means for supporting supplies of bulbs and bases adapted for assembly, a receptacle containing an adhesive material, means for transferring adhesive therefrom and applying it to restricted oppositely disposed outer areas of a bulb, means for causing a relative movement between the bulb and a base to bring them into assembled relation, means for applying pressure between the bulb and base to spread the adhesive, and means for applying pressure in a direction substantially at right angles thereto to insure the bulb and base being attached in predetermined relation by the coherence of the adhesive.

40 6. In an apparatus for assembling incandescent lamp bulbs with their supporting bases, means for supporting supplies of bulbs and bases, a receptacle containing an adhesive material, means for transferring adhesive therefrom and applying it to diametrically opposed restricted areas of a bulb, means for causing relative movements between the bulb and a base to assemble them in attached relation by the coherence 45 of the adhesive, and means for accelerating the hardening of the adhesive.

7. In an apparatus for assembling incandescent lamp bulbs with their supporting bases, means for individually supporting a supply of bulbs, means operatively associated therewith for positioning the bulbs in a predetermined position thereon, a receptacle containing an adhesive material, means for transferring adhesive therefrom and applying it to diametrically opposed restricted areas of a bulb, means for supporting a supply of bases, and means for transferring a base therefrom to the bulb and causing them to be assembled in attached 60 relation by the coherence of the adhesive.

8. In an apparatus for assembling incandescent lamp bulbs with their supporting bases, a plurality of traveling carriers for supporting a supply of bulbs, a plurality of magazines for supporting a supply of bases, a receptacle containing an adhesive material, means for transferring adhesive therefrom and applying it to diametrically opposed restricted areas of a plurality of bulbs supported on the carrier in one position thereof, means for transferring bases from the magazines in axial alignment with respect to the bulbs previously treated with adhesive, means for causing a relative movement between the bulbs and bases to assemble them in a predetermined attached relation by the coherence of the adhesive, and means for actuating the carriers and the several aforementioned means.

9. In an apparatus for continuously assembling incandescent lamp bulbs with their supporting bases, a plurality of intermittently actuated traveling carriers for supporting a supply of bulbs, a magazine for supporting a supply of bases, a receptacle containing an adhesive material, means for transferring a predetermined amount thereof to a restricted area of a bulb supported by one of the carriers in one position thereof, means for transferring a base from the magazine to the bulb in another position thereof to assemble the bulb and base in attached relation by the coherence of the adhesive, an oven for hardening the adhesive, the carriers traveling therethrough with the lamp assemblies, means for ejecting the completed lamp assemblies from the apparatus, and means for actuating the carriers and the several aforementioned means in a predetermined sequence.

10. In an apparatus for assembling lamp bulbs with their supporting bases, means for individually supporting a supply of bulbs, means for supporting a supply of the supporting bases, a receptacle containing an adhesive material, means for transferring adhesive material from the receptacle and applying it to diametrically opposed surfaces of a bulb, means for causing a relative movement between the bulb and a supporting base to assemble them in attached relation by the coherence of the adhesive, a heated compartment for drying the adhesive of the assembled lamp and supporting base, a traveling carrier for conveying the assembled lamps through the heated compartment, and means for causing the carrier upon entering the compartment to travel a circuitous path in one general direction to a predetermined point and thence in another circuitous path in a reverse general direction to a point of exit from the compartment.

11. In an apparatus for assembling lamp bulbs with their supporting bases,

means for individually supporting a supply of bulbs, means for supporting a supply of the supporting bases, a receptacle containing an adhesive material, means for transferring adhesive material from the receptacle and applying it to diametrically opposed surfaces of a bulb, means for causing a relative movement between the bulb and a supporting base to assemble them in attached relation by the coherence of the adhesive, a heated compartment for drying the adhesive of the assembled lamp, a supporting base, an endless traveling carrier for conveying the assembled lamp through the compartment, a plurality of rotatable shafts for propelling the endless carrier, and means for driving the shafts, said shafts and driving means being so arranged that the carrier upon entering the compartment is caused to travel a circuitous path in one general direction to a predetermined point and thence in another circuitous path in a plane surrounded by the first path and in a reverse general direction to a point of exit from the compartment.

12. In an apparatus for assembling an article with a supporting member, a receptacle containing an adhesive material, means for transferring adhesive material therefrom and applying it to oppositely disposed restricted areas of the article, and means for causing a relative movement between the article and the member to assemble them in attached relation by the coherence of the adhesive.

13. In an apparatus for assembling an article with a support, a receptacle containing an adhesive material, means for transferring adhesive material from the receptacle and applying it to the article, means for causing a relative movement between the article and the support to assemble them in predetermined attached relation by the coherence of the adhesive, and means for thereafter polishing and trimming a surface of the support.

14. In an apparatus for assembling an article with a supporting base, means for holding a supply of articles, means for holding a supply of supporting bases, a receptacle containing an adhesive material, means for transferring adhesive material from the receptacle and applying it to a restricted area of an article, means for causing a relative movement between the article and a supporting base to bring them into assembling relation, and means for subjecting the article and the supporting base to pressure to press them into more intimate contact with each other.

In witness whereof, I hereunto subscribe my name this 30th day of November, A. D., 1926.

CHARLES WALES.
